UNITED STATES PATENT OFFICE

VICTOR H. PALM, OF BUTLER, PENNSYLVANIA

INTERNAL-COMBUSTION ENGINE

Application filed April 13, 1928. Serial No. 269,697.

This invention relates to internal combustion engines and more particularly to improvements in such engines which render them more economical and powerful and which is especially adapted to increase their operating efficiency.

In accordance with my invention I provide an engine working on the two-cycle stroke having four power cylinders and four charging pumps for scavenging cylinders in tandem, with the crank shaft cranks on the quarter and with the pistons of each pump ninety degrees in the lead of the power cylinder with which it is aligned.

The invention further provides a rotary valve for timing the high pressure air for starting the engine or for driving it, the rotary valve also functioning to control the inlet passages to different pump cylinders.

The invention will become more apparent from a consideration of the accompanying drawings, in which like reference characters designate like parts and in which Fig. 1 is a side elevational view of a four cylinder internal combustion engine embodying the principles of this invention; Fig. 2 is a sectional elevational view thereof taken along the line II-II, Fig. 1; Fig. 3 a cross-sectional view of the pump piston illustrating the piston rod and connecting rod connections with the piston member; Fig. 4 a longitudinal sectional view of the rotary valve taken along the line IV-IV, Fig. 5; Fig. 5 a vertical sectional elevational view of the rotary valve; Fig. 6 a sectional view of the valve shown in Fig. 5 taken along the line VI-VI thereof; Fig. 7 is a side elevational view of the valve bushing, and Figs. 8 and 9 are side and bottom elevational views of the rotary valve.

Referring to Fig. 1 of the drawings, the invention contemplates a utilization of four power cylinders 1, 1^a, 1^b and 1^c, and four pumping cylinders 2, 2^a, 2^b and 2^c, the cylinders being arranged in tandem in the order named. As shown in Fig. 2, the pumping cylinder 2 is mounted on a crank case 3 in which the crank shaft 4 is rotatably journalled. The power cylinder 1 is provided with a cylinder head 5, an inlet port 6, an exhaust port 7 and piston 8, the latter control-

ling the port 7 in its reciprocating movement to establish connection with the atmosphere through the exhaust passage 9. The cylinder head 5 and cylinder 1 are provided with spaces 10 and 11 for cooling the overheated parts in a customary manner. An intermediate head 12 is disposed between cylinders 1 and 2 and is provided with a stuffing box 13 for packing a piston rod 14 that connects the power piston 8 with a piston 15 of the pump cylinder 2. A port 16 is provided between the piston 8 and the intermediate head 12 to provide for the ingress and egress of air for cooling the underside of the power piston 8.

In the construction shown, the piston rod 14 is held in central alinement by the stuffing box 13 which steadies the pistons 8 and 15 in operation to prevent undue wear on the cylinder walls. The pump piston 15 is connected by a wrist pin 17 to connecting rod 18 which is journalled on a crank 19 of the crank shaft 4.

The cam shaft 20 is journalled in the crank case in parallel alinement with the crank shaft 4 and is rotated at the same speed as the crank shaft through a train of gears 21 and 22 which are more clearly shown in Fig. 1 of the drawings. The shaft 20 carries cams 23 which actuate cam rollers or followers 24 that are mounted on the ends of the push rods 25 which operate inlet valves 26 that control the inlet passages 6 of the power cylinders. The valves 26 are biased by coil springs 27 to closed or seating position, the spring 27 resting against the spring seats 28 and 29, the latter being adapted to engage a strip 30 on the push rod 25.

The valve 26 is provided with a sleeve 31 of substantially the same surface area as the valve seat to balance the valve against pressures conducted through the intake port 32, the balance sleeve 31 being ring-sealed at 33 to prevent loss of pressure past the sleeve 31. The pumping cylinder is provided with a plurality of passages 34 which are connected by manifolds 35, 36, 37 and 38 with the casing 39 of the rotary valve shown in Figs. 1 and 5 and ports similar to the port 34 are connected by manifolds 40, 41, 42 and 43 to the

inlet passage 32 leading to the valves 26. The heads 5 of the power cylinders are provided with fuel nozzles 45 which are provided with fuel lines 46 leading to a fuel injector pump 47, Fig. 1.

5 As shown in Fig. 1 the cam shaft 20 is geared by helical gears 48 and 49 to shaft 50 of the rotary valve 65, the shaft 50 operating at the same speed as the cam shaft and the latter is further provided with a spiral gear 51 which interacts with the gear teeth of the gear wheel 52 to operate a shaft 53 that actuates the injector pump 47 or which may be utilized to drive a magneto where an 10 ignition system is employed.

15 Referring to Figs. 4 and 5, the rotary valve for timing the high pressure air consists of housing 39 in which is mounted the shaft 50, the latter being journalled by antifriction 20 bearings 55. In the upper portion of the housing 39 a sleeve 56 is mounted for angular movement which is effected through a handle member 57 by means of which the sleeve 56 is movable between the limits of 25 strokes 58 and 59, Fig. 4. As shown in Fig. 4 the sleeve 56 is provided with a port 60 which is adapted to connect the valve with a high pressure port 61 or an air intake port 62 for a purpose to be hereinafter explained.

30 The valve casing 39 is provided with openings 63 which connect to the manifolds 35, 36, 37 and 38 leading to the pump cylinders. The stationary bushing 64 is secured in the housing 39 and a rotary valve 65 is fixed to the 35 shaft 50 and adapted to rotate therewith within the bushing 64. The lower portion of the valve housing 39 is further provided with a passage 66 which constitutes an exhaust port when the engine is operating under high 40 pressure or an inlet passage when the pump cylinders draw in air at atmospheric pressure as shown in Figs. 6, 7, 8 and 9; the bushing 64 and valve 65 are provided with L-shape ports 68 the circumferential length of which 45 is 70 degrees, four such ports being provided in the bushing 64 and one designated at 69 in the rotary valve 65. The valve 65 is further provided with an exhaust port 70 which is in line with the vertical leg 71 of the L-port 69 but disposed at an angle of 35 degrees therefrom for a purpose to be hereinafter stated.

50 The operation of the engine is briefly as follows:

55 For starting, the handle member 57 of the rotary valve is moved to the position where the port 60 is open to the inlet port 61 leading to a source of high pressure fluid and the latter will then, through the timing of the rotary valve be directed through the manifolds 60 35, 36, 37 and 38 to their respective pump cylinders to act upon the pistons for their down stroke thereby constituting the pumping cylinders power cylinders. On the up-stroke of the pumping pistons the air is compressed and is passed through the inlet pas-

5 sages 6 controlled by the valves 26 to the power cylinder where it is compressed on the up-stroke and, after the fuel is injected, finally expanded to operate the pistons 8. When the valve is used for timing the high pressure air 10 for starting the engine or for power when the demand on the engine is such as would ordinarily require the shifting of the transmission gears to a higher speed ratio, the air is admitted for about 140 degrees of the crank 15 travel, this being effected through the relation of the ports 68 and 69 which are 70 degrees, and on account of the rotary valve 65 operating at the same speed as the crank shaft, the ports will be open from the time they enter into alignment until they have passed 20 which is through a distance equal to the sum of the length of the ports and totals 140 degrees. The vertical legs of the L-shape port are the last to come into alignment and will 25 give a larger port opening until the point of cut-off.

30 The air expands about 35 degrees of the crank travel after the L-shape ports have been 35 cut off and the exhaust port 70 opened and remains open until the crank has travelled 40 15 degrees more, for the purpose of giving the air pressure time to exhaust down to atmospheric pressure which will just fill the charge pump cylinder with the proper amount 45 of air to transfer to the power cylinder to keep the latter working in the same manner as if the pump cylinder were drawing its air before it transferred it to the power cylinder.

50 In the operation of the engine, when the 100 piston 8 and the pump cylinder piston 15 are at their upper stroke, the power cylinder 1 is in position to fire and the pump cylinder 2 has transferred its air charge to the power cylinder 1^b which is at one-half of the compression stroke. The rotary valve will then be just opening into the manifold 35 and the manifold 36 will be open for one-half the stroke to the pump cylinder 2^a. The power cylinder 1^c has just completed its full stroke 105 and this cylinder has been scavenged by virtue of its exhaust port 7 being opened by the piston 8 passing it. The pump cylinder 2^b will be on the compression stroke and the cam 23 on shaft 20 will open valve 26 in the power 110 cylinder 1^c which will be scavenged until the piston 8 closes the exhaust port on the return stroke. The remainder of the air from pump cylinder 2^b will be forced into the power cylinder 1^c until the piston 15 in cylinder 2^b 115 has completed its stroke, when the valve 26 closes and piston 8 in power cylinder 1^c will compress the charge of air until the heat of compression will fire oil or fuel injected through the nozzle 45.

120 The foregoing description of the operation is for one revolution, but with the four cranks on the quarter, each power cylinder is brought into fire with each revolution, the rotation of firing when going ahead being 130

cylinders 1, 1^b, 1^c and 1^a. The pump cylinders operate to scavenge the power cylinders and charge air in the following sequence:— cylinder 2 delivers its charge to the power cylinder 1^b; 2^b to 1^c; 2^a to 1^a; and 2^a to 1. If the compression is not high enough so that the heat of compression will fire the fuel charged into the power cylinder, a spark may be utilized as is common for lower compression engines.

If the engine starts backward, the pump cylinders will not time right since the cranks being on the quarter will change their feed in relation to each other, and the rotation of firing likewise changes. The firing with the engine running backwards would be 1, 1^a, 1^c and 1^b and the pumps would be 2 to 1^a; 2^a to 1^c; 2^c to 1^b and 2^b to 1. From this it is evident that the engine will not run backwards without the cams starting inlet valves and the manifolds being changed to suit.

As previously explained, the exhaust port 70 in the rotary valve is in line with but not as long as the L-port 69 so that it will not open into the port 68 until it comes to the vertical L-part of it, thus making the timing right. The ports may vary in degrees of opening and exhaust under different engine speeds if need be. When the sleeve valve 56 is turned to open to the passage 62, the pump cylinders will draw their air from the atmosphere while the rotary valve L port 69 is travelling over the port 68 of the bushing, this being 140 degrees or leaving 35 degrees piston or crank travel before the exhaust port 70 opens and lets air come in to finish supplying the air in the pump cylinder. With this arrangement there will be full pump cylinder of air to scavenge the power cylinder and supply a new charge.

It is evident from the foregoing description of this invention that internal combustion engines formed in accordance therewith, may be scavenged and charged in a positive and efficient manner when operated in units of four cylinders on a two-stroke cycle. It is also evident that a single rotary valve for controlling the charging cylinders provide perfect timing and simple control for operating either under high pressure or when the charging pumps are drawing their own air.

Although one embodiment of the invention has been herein illustrated and described, it will be obvious to those skilled in the art that various modifications may be made in the details of construction and in the arrangement of the several co-operating parts without departing from the principles herein stated.

I claim herein as my invention:

1. An internal combustion engine comprising four power cylinders and four pumping cylinders arranged in tandem and having their pistons connected by a common piston rod, the cranks of the respective cylinders being on the quarter, valves controlling the in-

let passage of the power cylinder and a rotary valve geared at the cam shaft and adapted to rotate at the speed of the crank shaft said valve being adapted for timing the inlet passage of the charging pump cylinders for starting the engine by high pressure fluid and for opening the inlet passages of the pumping cylinders to the atmosphere to exhaust said cylinders to maintain a proper quantity of air charge for compression.

2. An internal combustion engine comprising a plurality of cylinders arranged in pairs the cylinders of each pair being in superposed relation, individual valves for controlling the inlet passages of the upper cylinders, and a valve timing device for controlling the passages of the lower cylinders, said valve timing device comprising a casing having L-shape ports therein, and a rotary member having an L-shaped port co-operating with said ports in succession.

3. An internal combustion engine comprising a plurality of cylinders arranged in pairs, the cylinders of each pair being in superposed relation and constituting power and pumping cylinders, pistons having reciprocating movement therein, piston rods joining each pair of superposed pistons, a crank-shaft, connecting rods for joining each pair of pistons with the cranks of the crankshaft to render the pistons of the various pairs of cylinders operative in a predetermined succession, passages for conducting fluid from the leading pumping cylinders to the succeeding power cylinders, valves for controlling said passages, and a valve device having ports connected to the inlets of said pumping cylinders, said valve device controlling the opening and closing of said ports successively and admitting fluid under pressure to one of the pumping cylinders on the downstroke of its piston and means to open said port to permit the fluid pressure to exhaust.

4. In an internal combustion engine, the combination of a plurality of pairs of cylinders consisting of a pumping cylinder and a power cylinder arranged in tandem, a piston in each cylinder and connected by a common piston rod, each pair of pistons of the various pairs of cylinders operative in a predetermined leading relation to the succeeding pair, passages for conducting fluid from the leading pumping cylinders to the succeeding power cylinders, valves for controlling the flow of fluid through said passages, a valve timing device having stationary ports connected to the inlets of said pumping cylinders, for controlling the ingress of fluid to said passages and said cylinders, and a rotary port for controlling the opening and closing of said stationary ports successively.

5. In an internal combustion engine, the combination of a plurality of pairs of cylinders consisting of a pumping cylinder and

- a power cylinder arranged in tandem, a piston in each cylinder and connected by a common piston rod, each pair of pistons of the various pairs of cylinders operative in a predetermined leading relation to the succeeding pair, passages for conducting fluid from the leading pumping cylinders to the succeeding power cylinders, valves for controlling the flow of fluid through said passages, 5 a valve timing device having stationary ports connected to the inlets of said pumping cylinders for controlling the ingress of fluid to said passages and said cylinders, and a rotatable member co-operating with said stationary ports and in timed relation thereto, 10 said rotatable member having one inlet port and one exhaust port.
6. An internal combustion engine as set forth in claim 4, in which the stationary ports and the rotary port of the valve-timing device are L-shaped and arranged to have their maximum openings at the point of cut-off. 15
7. In an internal combustion engine, the combination with a plurality of pumping cylinders, of a power cylinder in associated relation to each pumping cylinder, an inlet passage connecting each of the pumping cylinders to the succeeding power cylinder, valves for controlling said passages, a valve-timing device for controlling the passages of the pumping cylinders, and pistons in each of said cylinders for compressing a charge of fluid in one of the pumping cylinders and delivering the charge to the succeeding power cylinder during the compression stroke of the said pistons. 20
8. In an internal combustion engine, the combination with a plurality of pumping cylinders, of a power cylinder in associated relation to each pumping cylinder, an inlet passage connecting each of the pumping cylinders to the succeeding power cylinder, valves for controlling said passages, a valve-timing device for controlling the passages of the pumping cylinders, and pistons in each of said cylinders for compressing a charge of fluid in one of the power cylinders by the combined action of the said pistons in the power cylinder and its co-acting pumping cylinder during the compression stroke thereof. 25
9. An internal combustion engine, comprising a plurality of cylinders arranged in pairs, the cylinders of each pair being in superposed relation and constituting power and pumping cylinders, pistons having reciprocating movement therein, piston rods joining each pair of superposed pistons, a crankshaft, connecting rods for joining each pair of pistons with the cranks of the crankshaft to render the pistons of the various pairs of cylinders operative in a predetermined succession, passages for conducting fluid from the leading pumping cylinders to the succeeding power cylinders, valves for 30

controlling said passages, and a valve device having ports connected to the inlets of said pumping cylinders, said valve device controlling the opening and closing of said ports successively and admitting a supply of air from the atmosphere to one of the pumping cylinders during substantially the greater parts of the intake stroke of its piston and having means to establish communication between said pumping cylinder and the atmosphere to admit a complete supply of air to the pump cylinder. 70

In testimony whereof I, the said VICTOR H. PALM, have hereunto set my hand.
